CLAIM

The ornamental design for a vacuum cleaner, as shown and described.

DESCRIPTION

FIG. 1 is a perspective front, top, left view of a vacuum cleaner showing the claimed design;

FIG. 2 is a perspective front, top, right view of FIG. 1;

FIG. 3 is a perspective front, bottom left view of FIG. 1;

FIG. 4 is a perspective front, bottom right view of FIG. 1;

FIG. 5 is a perspective rear, top, right view of FIG. 1;

FIG. 6 is a perspective rear, top, left view of FIG. 1;

FIG. 7 is a perspective rear, bottom, right view of FIG. 1;

FIG. 8 is a perspective rear, bottom, left view of FIG. 1;

FIG. 9 is a front view of FIG. 1;

FIG. 10 is a rear view of FIG. 1;

FIG. 11 is a right view of FIG. 1;

FIG. 12 is a left side view of FIG. 1; and,

FIG. 13 is a top view of FIG. 1.

The broken lines shown in the drawings are for the purpose of illustrating portions of the vacuum cleaner and form no part of the claimed design.

1 Claim, 13 Drawing Sheets
